FOUNTAIN ROLLER DRIVE

Charles A. Harless, Riverside, Conn., and Emory W. Worthington, Dobbs Ferry, and Albert T. Zurick, Bronx, N. Y., assignors to R. Hoe & Co., Inc., New York, N. Y., a corporation of New York

Application March 29, 1954, Serial No. 419,364

9 Claims. (Cl. 101—363)

This invention relates to ink motion drives for printing machines and more particularly to oscillating rotary drives, such as are used with ratchet driven ink fountain rollers.

It is an object of the invention to provide a completely enclosed drive of the type indicated.

A further object is to provide a drive of the type indicated which may be adjusted while the machine is running and which provides close adjustment of the arc of movement of the rotary oscillating shaft, while eliminating slidable parts.

With these objects, and still other objects which will appear, in mind, a drive mechanism embodying the invention in a preferred form will now be described with relation to the accompanying drawings and the features forming the invention will then be pointed out in the appended claims.

In the drawing:

Figs. 1 and 2 are schematic diagrams of a mechanical movement used in the drive of the invention;

Fig. 3 is an elevation view of the drive mechanism, looking in the direction of line 3—3 of Fig. 5, and with the housing cover broken away;

Fig. 4 is a fragmentary section on line 4—4 of Fig. 3;

Fig. 5 is a section on line 5—5 of Fig. 3;

Fig. 6 is a fragmentary elevation of a part of the mechanism of Fig. 3, with the cover and associated parts in place;

Fig. 7 is an elevation showing a device similar to that of previous figures but adapted for placement in reversed position with relation to the ink drum of the ink motion.

In Fig. 1, there is shown, in schematic form, a mechanical movement or linkage used to obtain an oscillating rotary movement. Shaft 1, continuously driven off the printing machine drive, carries crank 2 pivotally connected at 4 to a pitman or link 3, the other end of which is pivotally connected at 5 to one end of an idle crank or rocker arm 6, whose other end is pivotally mounted at 8 on an angularly adjustable sector plate 9. A link or pitman 7, also pivotally connected to arm 6 at point 5, is pivotally connected at its other end 10 to driven crank 11 fixed to a shaft 12 which drives the fountain roller through a suitable ratchet or one way clutch. A ratchet drive such as shown in Harless application, Serial No. 323,845, filed December 3, 1952, for ratchet, may be used.

Sector plate 9 is swingably carried on a shaft 13 and is angularly adjusted by a worm 15 engaging worm wheel teeth 14 formed on the plate 9. The position of plate 9 is indicated by a pointer 16 (Fig. 6) reading on a scale 17 and it may be locked in adjusted position by a cam block or wedging device 18.

The plate 9 is shown in Fig. 1 as adjusted for maximum movement of the shaft 12, the positions of the parts in the two extreme positions being indicated by full and phantom lines, respectively. A full rotation of shaft 1 will rock arm 6 about the pivot 8 through about a 60° angle, as indicated. In Fig. 2, the plate 9 is shown as adjusted

2

for minimum movement of the shaft 12. In this case, the driven crank 11 remains stationary, pivots 8 and 10 are coaxial, and arms 6 and 7 merely swing back and forth about these coaxial pivots in unison as the shaft 1 rotates.

5 By setting sector 9 in a position intermediate between the positions of Figs. 1 and 2, any desired intermediate angle of oscillation of shaft 12 may be obtained.

At the extreme position of crank arm 11, as shown in full lines in Fig. 1, the pivots 5 and 4 and the axis of shaft

10 1 will necessarily be aligned, so that in going from this position to the extreme position shown in phantom lines, both links 3 and 7 will be in tension rather than compression. By selecting the working stroke of the driven ratchet in this direction, the weight of the parts may be very much reduced as rocker arm 6 is the only link operating in compression.

Arms 6 and 7 being of the same length, it will be apparent from the foregoing description that full adjustment down to zero stroke will be insured if an adjustment

20 sufficient to bring pivot 8 to a position where its distance from the axis of shaft 12 is the same as that of the pivot 10. A difference in length between crank arms 2 and 11 is not required to convert from continuous to oscillating rotary movement and both these members may therefore

25 be made relatively short and correspondingly strong, as the arc of oscillation is determined essentially by the ratio between the lengths of arms 2 and 6 and the positioning of the fixed centers of shafts 1, 12 and 13.

In Figs. 3 to 6, the above-described linkage is shown in

30 the form it assumes in the actual machine, the elements being designated by the same reference numerals as already used.

The parts are contained in a combined housing and frame structure formed as a casting 20, fastened to the ink motion frame 21 (Fig. 5) by bolts 22.

This casting is open at one side, where it faces the frame 21 and at the other where it is closed off by a cover plate 23 fastened to it, as by means of screws.

The casting 20 is formed with a central partition wall or web 25, suitably thickened to form solid supports for the parts, and

35 with a further partial web or partition 26 (Fig. 4) also suitably thickened for the same purpose. The casting 20 thus constitutes a compartmented unitary frame structure.

The linkage mechanism is positioned outwardly of web 25 and the machine gearing is accommodated in the space between this partition and the machine frame.

The structure of the linkage will be clear in general from the description of Figs. 1 and 2 above. The details of the structure will now be further explained. Driving

40 shaft 1, previously referred to is shown as supported in a bearing 30 in the machine frame 21 (Fig. 5) and extending through partition 25 where additional bearing support is provided. Crank 2 has a split hub and is

45 fixed to the shaft 1 by clamping the hub to this shaft by means of tightening screw 31 (Fig. 3). Driven shaft 12 passes through the machine frame 21 and web 25,

50 being journaled in this web (and also supported inwardly of the frame 21 at the ratchet drive, not shown). Crank arm 11 is fixed to this shaft by means of a split hub and screws 32. Shaft 13 (Fig. 4), the remaining fixed

55 center of the linkage is journaled in partition web 26 and its outer end is also supported by the cover 23. The

worm 15, cooperating with worm wheel sector 14 on the plate 9, is rotatably carried by casting 20 as shown

60 in Fig. 3 and has a handle 33, exterior to the housing, by turning which the plate 9 may be adjusted. Link 3 is formed with a fork 34 receiving the end 33 of link 7, and is in turn received within a fork 36 at the end

65 of rocker arm 6. This last element is relatively wide (Fig. 3) and thick (Fig. 5) as it operates in compression.

The end of shaft 13 (Fig. 4) extends through cover

70 23 and carries pointer 16 cooperating with scale 17 outside the cover. Locking member 18 (Figs. 1 and 5)

is carried inside the cover on a bolt 40 having a threaded outer end which carries a nut 41 having an operating handle 42. By turning nut 41 member 18 may be drawn up to clamp plate 9 against the cover 23 and lock it against movement, while turning nut 41 in the reverse direction releases the plate 9 for adjustment by worm 15.

As is apparent, casing 20 is divided into an outer space accommodating the linkage described above, and an inner space adjacent the machine frame 21, which accommodates further gearing. This gearing includes an idle gear 50 (Figs. 3 and 5), carried by means of anti-friction bearings 51 on a shaft 52, one end of which is supported in a bore 53 in the frame 21 and held in position axially by an enlarged portion 54, and the other end of which is supported in the partition 25. A smaller gear 55 is fixed to the gear 50 for rotation therewith. This gear 55 drives an idle gear wheel 56 and smaller gear 57 fixed thereto, gears 56, 57 being supported from frame 21 and partition 25 in the same way as the gears 50, 55. Gear 57 meshes with and drives gear 58 fixed to the shaft 1, and thus drives the linkage above referred to. The idle gear 50 is driven from the machine as by means of gearing 60, 61.

It will be observed that all elements within the inner space of the housing 20 may be placed in position and the housing may then be slid over the protruding shaft ends, following which the elements of the linkage may then be put in place, providing a very convenient and simple assembly.

What is claimed is:

1. An oscillating rotary drive for ink motion fountain roller ratchet drives comprising a frame and housing structure adapted for attachment to a printing machine frame, the said frame and housing structure having a partition wall dividing it into an inner space for accommodating ink motion gearing and an outer space for accommodating an oscillating drive for the fountain roller ratchet, a continuously driven drive shaft and oscillating driven shaft, openings through the said partition wall accommodating said shafts, an adjustable linkage in the outer space and carried by the partition wall, and means operable externally of the housing for adjusting the linkage to vary the arc of oscillation of the driven shaft.

2. An oscillating rotary drive for ink motion fountain roller ratchet drives comprising a frame and housing structure adapted for attachment to a printing machine frame, the said frame and housing structure having a partition wall dividing it into an inner space for accommodating ink motion gearing and an outer space for accommodating an oscillating drive for the fountain roller ratchet, a continuously driven shaft and oscillating driven shaft, openings through the said partition wall accommodating said shafts, an adjustable linkage in the outer space comprising crank arms removably secured to the said shafts; a stroke adjusting member pivotally carried by the housing and links connecting the said crank arms and stroke adjusting member, and means operable externally of the housing for adjusting the stroke adjusting member to vary the arc of oscillation of the driven shaft.

3. An oscillating rotary drive according to claim 2,

comprising also a further and partial partition in the outer space of the said housing and carrying the said adjustable member.

5. An oscillating rotary drive for ink motion fountain roller ratchet drives comprising a frame and housing structure adapted for attachment to a printing machine frame, the said frame and housing structure having a partition wall dividing it into an inner space for accommodating ink motion gearing and an outer space for accommodating an oscillating drive for the fountain roller ratchet, a continuously driven driving shaft and oscillating driven shaft, openings through the said partition wall accommodating said shafts, an adjustable linkage in the outer space comprising crank arms removably secured to the said shafts, a stroke adjusting worm wheel sector pivotally carried by the housing and links connecting the said crank arms and stroke adjusting member, and a worm rotatably carried by and operable externally of the housing for pivoting the stroke adjusting worm wheel sector to vary the arc of oscillation of the driven shaft.

6. An oscillating rotary drive according to claim 4, comprising also a further and partial partition in the outer space of the said housing and carrying the said worm and worm wheel sector.

7. An oscillating rotary drive according to claim 5, comprising also a removable cover plate for the housing and having an aperture aligned with the worm wheel sector pivotal axis and an indicator shaft rotatable with the worm wheel sector and extending through the said aperture.

8. An oscillating rotary drive for ink motion fountain roller ratchet drives comprising a frame and housing structure adapted for attachment to a printing machine frame, the said frame and housing structure having a partition wall dividing it into an inner space for accommodating ink motion gearing and an outer space for accommodating an oscillating drive for the fountain roller ratchet, a continuously driven driving shaft and oscillating driven shaft, and an adjustable linkage in the outer space and carried by the partition wall and means operable externally of the housing for adjusting the linkage to vary the arc of oscillation of the driven shaft, and a further housing removably connected to the first said housing structure at one side and accommodating the gearing for driving the said ink motion gearing and ratchet drive in a predetermined direction.

9. An oscillating rotary drive according to claim 7, in which the said idle gearing is arranged for driving the said drive shaft in the same direction as a gear in mesh with and driving the idle gearing.

10. An oscillating rotary drive according to claim 7, in which the said idle gearing is arranged for driving the said driving shaft in the opposite direction to a gear driving the idle gearing.
